UNITED STATES PATENT OFFICE.

CESARE BARBIERI, OF NEW YORK, N. Y., ASSIGNOR TO THE VORTEX MFG. CO., A CORPORATION OF ILLINOIS.

SUNDAE DISH AND METHOD OF MANUFACTURE.

Application filed September 21, 1921. Serial No. 502,212.

To all whom it may concern:

Be it known that I, CESARE BARBIERI, a subject of the King of Italy, and a resident of the city of New York, in the county of New York and State of New York, have invented certain new and useful Improvements in a Sundae Dish and Method of Manufacture; and I do hereby declare that the following is a full, clear, and exact description of the same, reference being had to the accompanying drawings, and to the numerals of reference marked thereon, which form a part of this specification.

This invention relates to improvements in sanitary dishes for dispensing ice cream sundaes or the like, and has for one of its objects the provision of such a dish which is more economical to manufacture than the dishes which have heretofore been used.

Another object of this invention is the provision of a dish of prepared material, usually paper or the like which has been impregnated with paraffin or some other waterproofing substance, which can be readily manufactured and economically shipped on account of the greater convenience in packing the same in its finished form.

Still another object of this invention is the provision of an improved sundae dispensing dish of a conical form which is made from a circular piece of prepared material, a portion of the prepared blank having been omitted in the formation of same in order to effect a saving of the material, but by the improved method of this invention the blank is folded in such a manner as to form a complete and finished dish from a blank which is not wholly circular in form.

Other and further important objects of this invention will be apparent from the disclosures in the accompanying drawings and following specification.

The invention (in a preferred form) is illustrated in the drawings and hereinafter more fully described.

On the drawings:

Figure 1 is a plan view of a portion of a strip or sheet of prepared material showing the manner in which the blanks are formed or cut therefrom.

Figure 2 is a plan view of a blank from which a dish is made.

Figure 3 is a side elevation showing a finished dish. 55

Figure 4 is a view similar to Figure 3 showing a slight modification of the method of forming the dishes.

Figure 5 is a perspective view showing the method of packing a plurality of the manufactured dishes. 60

Figure 6 is a plan view of a completed dish folded for packing.

Figure 7 is an end elevation of the dish shown in Figure 6. 65

Figure 8 is a top plan view of a completed dish.

As shown on the drawings:

The reference numeral 10 indicates a portion of a sheet or strip of paper or other material, from which the blanks 12 are cut, the same having been previously prepared by being impregnated with paraffin or some other waterproofing composition. As shown in Figure 2, the blanks 12 are not entirely 70 circular in form but a portion is omitted as shown at 14, this cut-out portion being due to the overlapping of the circular cutting dies by means of which the blanks are cut from the strip of prepared material 10. In the manufacture of the dishes a triangular portion 16 is folded over an adjacent triangular portion, these triangular portions each having its apex at the center of the blank, two of the sides being radii of the 75 circular blank and ending at the points where the cut-out portion 14 begins along the periphery of the blank 12. As shown in Figure 4, this results in the formation of a conical-shaped dish having its folded over portions 16 concealing the indentation 14. 80

If desired, the blank may be folded as shown in Figure 3 where each of the folded over triangular pieces 16 includes one-half of 85 the indented portion 14 which also effectively brings the indented cut below the top or rim of the cut, and allows of the formation of a smooth unbroken edge. This folding of the circular disk into suitable shape 90 is accomplished by means of a machine provided for the purpose having triangular gripping and folding members. As shown in Figure 8, the completed conical dish 18 has an unbroken edge or rim extending entirely around the top thereof and the cut-out 95 100 105

portion 14 is folded under in such a manner as to be unnoticeable from the top of the dish or when looking down at the same. If desired, the fold may be made as shown in Figure 3, the parts adjacent the cut-out portion 14 being folded or doubled over in two sections to correspond with each other.

In order to be economically packed into the most convenient form for shipping and in such a manner as to require a minimum of space, the dishes are each folded once into the form shown in Figures 6 and 7. The dish is first folded along the outer line of one of the triangular folds 16 and a corresponding crease 20 is made directly opposite and in line with the same to allow of the dish being folded into a flat shape as shown in Figure 7, and a plurality of the folded prepared dishes may be assembled in compact form for packing as shown in Figure 5.

It will be seen that herein is provided a conical dish and a method of making the same wherein a minimum of material is used in forming the completed receptacle, which method results in the saving of quite a considerable portion of the material from which the dishes are formed as best shown by the dotted lines in Figure 1 which illustrate the amount of saving accomplished in the manufacture of three of the dishes or the cutting of three of the blanks which saving of course will increase directly in proportion as the number of blanks cut or dishes manufactured.

The method of folding and packing the completed dishes is also quite effective, especially regarding the great saving in space which results from the new and improved method of folding and packing the completed dishes, which have heretofore been packed and shipped in nested concave form. Moreover, the dishes, after being thus folded, may be readily opened into proper shape whenever desired for use.

I am aware that many changes may be made and numerous details of construction varied throughout a wide range without departing from the principles of this invention, and I therefore do not purpose limiting the patent granted hereon otherwise than necessitated by the prior art.

I claim as my invention:

1. A blank for forming receptacles comprising a circular disk having a concave notch cut in the periphery thereof.

2. A blank for forming conical receptacles, comprising a piece of paraffin saturated paper in approximately the form of a circular disk but with an indentation in the circumference thereof, said indentation be-

ing in the form of an arc of a circle of the same radius as the circle comprising the disk.

3. A blank for forming receptacles including a disk of prepared material having a portion of the periphery thereof cut away, said cut away portion being in the form of an arc of a circle of the same radius as the circle comprising the disk.

4. A blank for forming a conical receptacle comprising a piece of material having a concave notch cut in the periphery thereof.

5. A conical dish formed of a properly folded piece of material approximately circular in form having an indentation in the periphery thereof and concealed between two overlapping portions of the dish.

6. A conical dish formed of a properly folded piece of prepared material approximately circular in form having an indentation in the periphery thereof and concealed in the folded over portions of the dish, said folded over portion being in two layers, one of which is completely concealed and includes the indentation in the circumference of the prepared blank.

7. A method of preparing blanks for the manufacture of conical receptacles, including the cutting of a piece of prepared material into approximately circular disks, each disk having a cut-out portion in the periphery thereof formed by overlapping the cutting member of the adjacent disk thereover.

8. A method of forming conical dishes from prepared blanks approximately circular in form but with a portion of the periphery of each blank cut away, said method including folding certain sections of the blank to form the same into conical shape, said folded over sections including and concealing the indentations in the peripheries.

9. A method of forming a conical dish from a prepared blank approximately circular in form, but with a portion of the periphery of the blank cut away, said method including folding certain sections of the blank to form the same into conical shape with overlapping sections, said overlapping sections enclosing and concealing therebetween a section including the indentation, said section further being approximately triangular in shape and having two sides thereof corresponding to radii of the circle comprising the blank.

In witness whereof I have hereunto subscribed my name in the presence of two subscribing witnesses.

CESARE BARBIERI.
